CLAIM

The ornamental design for earphone, as shown and described.

DESCRIPTION

FIG. 1 is a left side isometric view of an embodiment of a listening device showing our new design;

FIG. 2 is a rear elevation view thereof;

FIG. 3 is a front elevation view thereof;

FIG. 4 is a top plan view thereof;

FIG. 5 is a bottom plan view thereof;

FIG. 6 is first side elevation view thereof;

FIG. 7 is a second side elevation view thereof;

FIG. 8 is right side isometric view thereof, with the listening device shown having an upper portion extended relative to a lower portion; and

FIG. 9 is an additional rear elevation view thereof, with the listening device shown having the upper portion extended relative to the lower portion;

FIG. 10 is an additional front elevation view thereof, with the listening device shown having the upper portion extended relative to the lower portion;

FIG. 11 is an additional top plan view thereof, with the listening device shown having the upper portion extended relative to the lower portion;

FIG. 12 is an additional bottom plan view thereof, with the listening device shown having the upper portion extended relative to the lower portion;

FIG. 13 an additional first side elevation view thereof, with the listening device shown having the upper portion extended relative to the lower portion; and,

FIG. 14 is an additional second side elevation view thereof, with the listening device shown having the upper portion extended relative to the lower portion.
